LOCOMOTIVE WEDGE BOLT ATTACHMENT

Filed May 29, 1929

F'x G. 2.

FIG. 2.

FIG. 4.

By Milo B. Kremersky

Attorneys

UNITED STATES PATENT OFFICE

JESSE L. GOSNELL, OF ST. JOSEPH, MISSOURI

LOCOMOTIVE WEDGE BOLT ATTACHMENT

Application filed May 29, 1929. Serial No. 366,939.

My invention relates to improvements in adjusting devices for the bearing boxes of locomotives and it has for its primary object to provide a very compact, simple and highly efficient device for the purpose specified; one which involves a minimum number of parts and which can be readily applied to the binder at the lower end of the pedestal within which the driving box is located,—and this without modification of the parts referred to and without modification of the adjusting wedge and worm shaft commonly employed—it being possible to apply my device using the same bolts that are now provided in all constructions now for supporting the device which my invention is intended to supplant.

A further object of the invention is to provide a device for the purpose indicated which can be applied without the necessity of removing the binder, which is of considerable advantage over prior devices of this kind.

The invention also resides in certain novel features of construction, combination and arrangement of the various parts and in modes of operation, all of which will be readily understood and appreciated by those skilled in the art upon reference to the accompanying drawings in connection with the following detailed descriptive matter.

While the preferred form of the invention has been chosen for purposes of illustration, as required by the patent statutes,—yet it is to be understood that the invention is susceptible of considerable change and modification within the spirit and scope of the subject matter claimed hereinafter.

In the drawings, wherein the same reference characters have been used to designate the same parts in all views,

Figure 1 is a fragmentary elevational view showing a portion of the engine frame and illustrating the application of my invention to the adjusting wedge of one of the bearing boxes and its associated carrying pedestal;

Figure 2 is a cross sectional view taken on line 2—2 of Figure 1;

Figure 3 is a cross sectional view taken on the line 3—3 of Figure 1; and

Figure 4 is a group perspective view of the elements detached.

Referring specifically to the drawing, numeral 1 designates a portion of the locomotive frame; 2 the so called pedestal, having the upright bars 2^a, 2^b at the sides between which reciprocates the driving box of bearing box 3 within which is shown the axle 4. Surmounting the bearing box 3 is the saddle 5 which transmits the weight of the frame to the box 3 through the leaf spring 6 in the usual manner. This is a more or less conventional construction which varies in the different locomotives.

It is also customary to provide the bar 2^b of the pedestal with a facing or bushing-like wear face 8 which is adapted to seat in the groove 9 of the bearing box 3, as indicated. The pedestal bar 2^a at the opposite side is provided with a similar face plate, which is designated at 10 and is received in a groove 9^a at the opposite side of the bearing box 3. The wedge 10 has a tapered surface 10^a corresponding to the angle of incline of the inner face 2^b of the bar 2^a, as clearly indicated in Figure 1. Thus, adjusting of the plate or member 10 through the instrumentality of the worm 11 depending from the lower end thereof, prevents transverse play of the box 3 in the pedestal 2. The worm 11 extends through the bar or binder block 12 which, as shown, closes the lower end of the pedestal 2 and may be secured by means of bolts 13 and nuts 14, as indicated. Obviously, the hole 12^a in the binder block 12, through which the worm 11 extends, will be slightly elongated to allow for slight movement in the direction of the width of the box 3, as the wedge 10 is moved.

The foregoing construction is more or less standard and no novelty is claimed therefor.

My invention resides in the provision of a novel U-shaped bracket member 20 having lateral arms 21 which have suitable holes to receive the bolts 13, 22 extending from the pedestal frame 2 whereby the U-shaped member may be securely bolted beneath said frame and against the binder block 12. The U-shaped frame 20 is provided with an inner U-shaped plate 23, which is secured against the arms of the first mentioned U-shaped plate by means of bolts 24. It is to be noted

that the ends of the second mentioned U-shaped plate 23 lie flush with the top surfaces of the lateral arms 21 so as not to interfere with the mounting of the first mentioned 5 U-shaped plate contiguous with the bottom of the binder bar 12. The space between the two U-shaped plates 20, 23 is adapted to receive a worm wheel 26 and the second mentioned U-shaped plate,—namely 23,—has a 10 hole through which the worm 11 is adapted to project. The worm wheel or gear 26 also has an internal worm adapted to mate with the worm 11. Therefore, when the worm wheel 26 is turned the worm 11 will be actuated to raise or lower the wedge 10.

The construction recited thus far is believed to be obvious.

The open side of the box-like space defined between the plates 20, 23, is adapted to be 20 closed at either side by means of closure plates 30, 31 from the inner faces of each of which project a transverse rib and boss, as denoted at 30^a, 30^c and 31^a, 31^c, respectively,—such bosses and ribs engaging the bight 25 portions of plates 20, 23 and the inner faces of the legs of plate 20 so as to locate the closure plates against shifting. Closure plates 30, 31 are held in place by pins or the like 30 extending through the respective bosses 35 and ribs to be received in holes 20^a, 23^a of plates 20, 23. A bearing hole 32 extends through the boss 30^c to receive the worm 33, which meshes with the worm wheel 26. The other boss-like portion 31^c has a bearing 40 34 receiving the end of the worm 33. The worm 33 has a squared end extension 33^a projecting from the outer face of the plate 30 whereby it can be turned by the application of a ratchet wrench or the like.

45 In conclusion it is believed to be obvious that the wedge 10 can be readily adjusted by simply inserting a ratchet wrench between the spokes of the engine wheel and engaging same with the squared end 33^a of the worm shaft 33. The device can be readily applied without removing the binder bar 12. Adjustments can be made by the engineer while on a trip, thus obviating the danger of 50 injury to the working parts through pounding of the bearing box in its pedestal and this without the necessity of crawling under the engine or attempting to manipulate nuts or other securing devices from an awkward position.

55 Having thus described my invention, what I claim as new and desire to secure by Letters Patent is:

1. In a pedestal carried wedge adjusting device for locomotives and the like, the combination of a pair of interfitting U-shaped plates having spaced bight portions providing a worm gear bearing, a worm gear seated between the bight portions of said plates, one of said plates having a hole through 60 65 which a worm is adapted to be extended, the

bore of said worm wheel having a worm thread, a worm shaft extending through said hole and engaging the bore of the worm gear, said worm shaft extending from the adjusting wedge of the pedestal, one of said U-shaped plates having right angularly extending arms adapted to receive bolts whereby the assembly may be mounted against the engine frame at the bottom of the pedestal, said U-shaped plates exceeding in width the diameter of said worm wheel, closure plates adapted to be mounted against each side of said U-shaped plates to close the space defined by the bight portions thereof, said closure plates having cleats extending against the inner surfaces of the leg portions of one of said U-shaped plates, clamping means for holding said closure plates in place, and a worm shaft carried by said plates and adapted to mesh with said worm wheel whereby the same can be manually adjusted, and said worm shaft having a projecting end beyond the surface of one of said plates for the application of a wrench.

2. In a device for application to the lower portion of the receiving frame of a locomotive journal box for controlling the movement of the wedge or wear plate, the combination of a bracket adapted to be secured against the bottom of said frame and providing a gear box open at either side, a worm wheel freely insertible in said gear box from one side thereof and having a worm threaded hub portion adapted to receive the worm shaft of the adjusting wedge, the bracket having a hole through which said worm shaft extends for access to said gear, closure plates for the sides of said gear box, and a second worm shaft carried by said closure plates and adapted to engage said worm wheel for turning the same, said adjusting shaft having one end extending beyond one of said closure plates for the application of a wrench.

3. In a wedge adjustment device for locomotive gear boxes wherein the wedge has a worm shaft adjustment element, a gear box applicable to the locomotive frame, a worm wheel having a worm threaded hub portion receiving the wedge adjusting worm, said gear box being open at either side, closure means for the side of said gear box, and actuating means for said worm wheel carried by said closure means.

In testimony whereof I affix my signature.

JESSE L. GOSNELL. 120
